UNITED STATES PATENT OFFICE.

JAMES HERVEY MANN, JR., OF PINE BLUFF, ARKANSAS, ASSIGNOR, BY MESNE ASSIGNMENTS, TO SOUTHWESTERN SALES CORPORATION, A CORPORATION OF DELAWARE.

FRAUD-PREVENTING MECHANISM FOR VENDING MACHINES.

Application filed December 4, 1920. Serial No. 428,304.

To all whom it may concern:

Be it known that I, JAMES H. MANN, Jr., citizen of the United States, residing at Pine Bluff, in the county of Jefferson and 5 State of Arkansas, have invented certain new and useful Improvements in Fraud-Preventing Mechanism for Vending Machines, of which the following is a specification, reference being had to the accompanying drawings.

The purpose of the present invention is to provide a mechanism of this kind, especially adapted for use in connection with vending machines generally, and particularly in connection with the type of machine illustrated, set forth and claimed in the copending application filed September 4, 1919, in the name of James H. Mann, Jr., Serial No. 321,611, for preventing a coin 10 controlled mechanism and article tray from being fraudulently operated.

Very often attempts are made to use slugs of different types, for operating the vending machine, instead of using the proper size 15 and denomination of coin, and in the present invention it is the aim to prevent the successful passage of the slug, especially should the slug be made of any magnetizable material, or too large or too small in 20 diameter or irregular in thickness, while permitting a coin of the proper diameter and denomination to be used, in order to operate the coin controlled mechanism and article tray.

Still another purpose resides in a mechanism of this general character wherein should an operator insert a slug of too large a diameter or irregular in thickness, and it should clog the coin chute or passage, 25 the mechanism will be prevented from being actuated by a proper size diameter of coin, when the next operator attempts to insert a coin.

A further object is to provide a mechanism of this character having a coin passage or chute, in the wall of which there is disposed a gravity depressed member which will be lifted by a coin of proper size and provide in connection with this member 30 a dog which, when an object of larger size

than the predetermined coin is inserted, will act to prevent the lifting of said member and thus prevent the downward passage of this article as, for instance, a blank or slug.

A still further object of the invention is to provide a machine of this character which is so constructed as to prevent the successful passage of a slug which, though of proper diameter and thickness, is lighter 55 than the predetermined coin to thereby prevent the vending machine from being operated by such a slug, the lower wall of the coin passage to this end being provided with a hurdle, as it may be termed, which 60 acts to arrest the light slug during its passage through the chute, thus preventing a coin of the proper diameter and denomination from being inserted in the mouth of the passage or chute.

Another object is to provide movable impediments in the wall of the coin chute or passage, these impediments being urged into an impeding position by gravity and being so arranged that a coin of the proper diameter and denomination and the required weight is capable of rolling movement 75 through the passage sufficient to overcome the gravity of this impediment and thereby permit the passage of the coin.

Moreover the present invention provides means located adjacent the coin slots and cooperating with the ends of the slots, so as to restrict the size of the slots, so that when inserting a coin of the proper diameter and denomination, it is necessary to force the coin through the slot, and in so doing, to raise the means against the action of tensioning means, to allow the coin to pass. The means comprising interconnected or 80 geared dogs adjacent the coin receiving slots are so tensioned and have their coin engaging ends so curved, that when the ends of the dogs pass the diameter of the coin, the dogs will be actuated by the tensioning means, to impart a pushing movement on the coin, and due to the momentum and the pushing movement, the coin will 85 successfully pass the hurdles, and eventually reach the coin controlled mechanism of the 90 100

vending machine, such as that shown in the above copending application.

As previously stated the fraud preventing mechanism is especially adapted for vending machines, such as that disclosed in said copending application; hence the entire machine when manufactured for commercial use will embody the coin controlled mechanism and the article tray of the machine in the copending application, together with the present mechanism.

In connection with the present invention, a still further aim is to provide means for arresting a slug of any suitable magnetizable material at a point in the passage or chute, thereby not only preventing the operator who inserted such a slug from receiving an article, but also so locking and preventing the parts of the mechanism from operating, that a successive or next operator is unable to operate the machine, in fact to even insert a coin, though it be of the proper diameter, denomination and weight. For instance should a slug of steel or any suitable magnetizable material be inserted in the passage, it will be arrested before it can reach the coin controlled mechanism, after which the operator will attempt to operate or push the actuator, which carries means adapted to cover the coin receiving slots. In this connection the invention aims to provide means cooperating with the arrested coin for preventing the actuator and the slot covering means from returning to their normal positions; hence the coin receiving slots will remain covered, and prevent other coins or slugs from being inserted.

Additionally the invention aims to provide a mechanism of this general character, whereby it may be locked, but still allowed to remain in a suspended position, in a public place where a machine of this character is used.

While the design and construction at present illustrated and set forth is deemed preferable, it is obvious that as a result of a reduction of the invention to a more practical form for commercial purposes, the invention may be susceptible of changes, and the right to these changes is claimed, provided they are comprehended within the scope of what is claimed.

The invention comprises further features and combination of parts, as will be hereinafter set forth, shown in the drawings and claimed.

In the drawings:—

Figure 1 is a perspective view of the type of vending machine in connection with which the present fraud preventing mechanism is used.

Figure 2 is a sectional view through the vending machine on line 2—2 of Figure 1 particularly through substantially one-half of the machine, at a point under the cover

for the fraud preventing mechanism, more clearly showing the mechanism with its parts in their normal positions.

Figure 3 is a view similar to Figure 2 showing the coin slot covering means carried by the actuator and partly covering the coin slots, hence locking the machine and preventing a coin from being inserted.

Figure 4 is a sectional view of the upper part of the vending machine, on a plan through the coin chute or passage, showing the intergeared dogs as having been actuated, with a coin of too large a diameter to engage in one of the coin slots.

Figure 5 is a detail perspective view of the rear wall or wall plate of the coin passage or chute.

Figure 6 is a detail perspective view of a portion of the coin slot covering bar.

Figure 7 is a detail perspective view of the dog which cooperates with a coin arrested by a horseshoe magnet for locking the actuator.

Figure 8 is a detail perspective view of the permanent horseshoe magnet, as casted or covered with "bakelite" or any other suitable insulating material, which prevents adjacent moving parts of the mechanism from being attracted.

Figure 9 is a detail perspective view of one of the pivots.

Referring more especially to the drawings, 1 designates the outer casing of the vending machine, which may be any suitable shape or configuration or any suitable construction preferably as shown, and therefore the same as the casing of the machine illustrated in the copending application. Mounted in the casing 1 is an inner casing 2, which is substantially similar to the inner casing shown in the copending application. The upper portions of the sides of the inner and outer casings are provided with coin receiving slots 3 and 4 which are in registration.

As previously stated the general construction of the present vending machine, particularly the coin actuated or controlled mechanism and article delivering tray (not shown) are designed to correspond with such mechanisms as in the copending application; therefore the actuator 5 is similar in construction. In the present application only the handle portion 6 of the actuator is shown in full, while the actuator proper is shown in dotted lines. Riveted to and carried by the actuator as indicated at 7 is a bar 8, which is guided by the guide flange 9 struck out from one of the side walls of the inner casing. It will be noted that a portion of the upper part of the actuator 5 is shown in full lines, as engaging a guide flange 10, which is struck up from the rear wall of the inner casing. The bar 8 is of the general construction, such as that shown in Figures 2, 3 and 6, and has an upper

transverse portion 11. The ends of the transverse portion 11 are rearwardly angled to provide lateral ears 12 positioned to move adjacent the inner faces of the sides of the 5 inner casing. These ears slide adjacent to the rear wall of the inner casing, and normally have their upper end edges 13 substantially even with the lower ends of the slots 3 and 4 of the sides of the inner and 10 outer casings. When the actuator 5 is pushed upwardly, the ears 12 will move over and cover the coin receiving slots 3 and 4, thereby preventing a successive coin from being inserted, until the actuator is allowed 15 to return to its normal position. A headed pin 14 is carried by the rear wall of the inner casing, and pivotally mounted thereon is a pawl 15. This pawl comprises a body 16 and an arm 17. The body, though it 20 may be any suitable shape, is preferably substantially elliptical, as shown, and is formed with a curved or scroll slot 18. The headed pin 14 normally engages through the end portion 19 of the slot, so that the 25 pawl may cooperate with the bar 8 in the manner shown clearly in the drawings. The arm 17 of the pawl terminates in an enlargement 20, which operatively engages between the shoulders 21 and 22, so that 30 when the actuator 5 is pushed upwardly, the bar 8 moves therewith, and the pawl 15 will move upon its pivot. A spring 23 has one end attached in any suitable manner to the rear wall of the inner casing. This attachment of the spring 23 to the rear wall 35 of the inner casing, is not shown, because the sectional views of Figures 2 and 3 only show half of the casing in section, and the other half in elevation. The other end of 40 the spring 23 is attached to a lateral lug 24 of the pawl 15. The spring 23 serves to tension the pawl, and through the medium of the arm of the pawl engaging between the shoulders 21 and 22 of the bar 8, the 45 actuator 5 is returned to its normal position after having been actuated. As shown in Figure 3 in dotted lines the pawl 15 may be moved to a position relatively to the headed pin 14, so that the shank of the pin may engage 50 the end portion 24^a of the slot 18, so that the pawl may operate on an entirely different fulcrum, and in this case when the actuator has been operated, the pawl will be prevented from actuating to allow the actuator 55 to return to its proper normal position. In other words due to mounting the pawl higher up, the end edge of the enlargement 20 of the arm of the pawl will contact with the inner face of one side of the inner casing 60 at a point higher up, thereby preventing the bar 8 which is carried by the actuator from returning to its normal position, or from moving its full stroke in a returned direction, as when the end 19 of the slot 18 65 is pivotally engaged by the headed pin.

In this case the projecting lug 25 of the bar 8 will not be allowed to pass a trip detent which is carried by a slug clearing pawl, hence holding the coin clearing pawl to a position in the path of the coin. When the 70 bar 8 and the actuator are prevented from being returned to their normal positions, the ears 12 remain as covering the slots 3 and 4, hence preventing a coin from being inserted. The magazine (not shown) is 75 adapted to have a rear wall, which is designed to cover the mechanism shown in Figure 2. Such a rear wall is disclosed in U. S. Letters Patent No. 1,408,112 issued February 28, 1922. When said magazine 80 is empty, and after removing the front slide cover of the casing and the rear wall, the actuator may be moved upwardly and the pawl 15 shifted, so that the end portion 24^a of the slot 18 of the pawl 15 may receive the 85 shank of the pivot 14, thereby preventing the actuator from returning to its normal position, and in this case the ears 12 will partially cover the slots 3 and 4.

It will be noted, as shown clearly in Figures 2, 3 and 4 that the back wall of the inner casing is provided with a depression 26, which is of an outline of the general contour as shown. The rear wall of the inner casing at a point above the upper part 90 of the depression 26 is provided with slots, and arranged in the upper part of the depression 26 is the rear wall of the coin passage or chute formed by a plate 27. The plate or rear wall 27 has angular lugs 95 100 29, which engage in the slots 28. The slots 28 are formed in the rear wall of the inner casing at a point immediately adjacent and in the upper wall of the depression 26, and by means of the lugs 29 engaging through 105 the slots 28, the plate 27 is held in place. This rear wall or plate 27 is mounted in the depression, so that its face, which forms the rear face of the coin passage or chute is 110 flush with the marginal portion of the rear wall of the inner casing, and is also flush with the rear longitudinal edges of the coin receiving slots 3 and 4.

Suitable pivots engage through the rear wall or plate 27, and through a forward 115 wall of the coin passage or chute constituted by a plate 30. The rear ends of the pivots 31, engage the rear wall of the depression 26, and the central portions of these pivots have enlargements 32, which act to space 120 the forward and rear walls. One of these pivots is shown in Figure 9. The ends of the pivots are swaged or otherwise headed, thereby riveting the forward and rear walls 125 or plates 27 and 30 in spaced relation. These plates are spaced apart to form a coin passage or chute, the opposite ends of which register with the coin receiving slots 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

may pass. Pivotally mounted upon the pivots 31 are coin gauging dogs 33, the adjacent ends of which are intergeared, by means of the arcuate interengaging teeth 34.

5 By this intergeared connection between the two dogs 33, the movement of one dog will cause the movement of the other. The noses 35 of the coin gauging dogs 33 are disposed adjacent the coin receiving slots 10 3 and 4, and the extremities of the noses are positioned a distance from the lower ends of the slots 3 and 4 less than the diameter of a coin of the proper denomination, thereby necessitating that some force 15 or pressure be used, to force the coin through the slots 3 and 4. It will be noted that when the extremities of the noses 35 pass the greatest diameter of the coin, the coin will readily pass into the passage or 20 chute.

The adjacent portions of the coin gauging dogs are provided with lugs 36, and extending from the upper edge of the wall or plate 30 of the coin passage or chute 25 are lugs 37. Connecting the lugs 36 and 37 are coiled tensioned springs 38, which act to hold the coin gauging dogs in their normal positions in contact with the projections or limiting stops 39, which are carried by 30 the upper edge portion of the plate or wall 30 of the coin chute or passage. The projections 39 extend rearwardly and overlie the upper edges of the dogs 33, so as to act as stops for the dogs.

35 The forward and rear plates or walls of the coin passage or chute are provided with arcuate slots 40, which are concentric with the pivots of the dogs 33. Engaging the slots 40 are gravity spherical balls or 40 weights 41, which constitute gravity actuated contractible sections of the upper walls of the coin passage or chute. In other words the lower edges of the dogs 33 constitute and bound the upper wall of the chute or passage, with the gravity actuated spherical members constituting sections of this wall. The arcuate slots 40 are positioned relatively to the pivots 31, so that when the gravity members 41 are moved to their uppermost 50 limit, only a coin of the proper diameter will barely pass. The dogs 33 are provided with notches 42 adjacent their pivots, which are adapted to straddle the balls 41, when the dogs 33 are raised through the medium 55 of a coin being inserted through either set of slots 3 and 4.

The lower portion of the rear wall of the coin passage or chute adjacent its central part has an arcuate edge, and adjacent the 60 ends of the rear wall or plate 27 of the coin passage or chute on opposite sides of the arcuate edge 43 have flanges 44, which are disposed angularly, and constitute angular bottoms or walls on which the coin is designed 65 to roll, in its movement through the chute.

These angularly disposed flanges 44 have lugs 45, which are riveted in the slots 46 of the forward plate or wall of the coin chute or passage, thereby more rigidly connecting the forward and rear walls or plates of the 70 coin chute or passage. It is obvious that when a coin is inserted through either set of coin receiving slots 3 and 4, it will move by gravity through the passage, and then into cooperative engagement with the coin controlled mechanism (not shown) of the vending machine, whereby an article may subsequently be vended. In addition to the flanges or bottoms 44, the rear wall or plate 27 has lugs 47 immediately adjacent the 75 lower ends of the flanges 44. The lugs 47 are arranged slightly higher than the lower ends of the flanges 44, thereby constituting hurdles in the path of a coin. A coin of proper diameter, denomination and weight 80 will receive momentum enough to pass over the hurdles or lugs 47. The momentum will be assured, due to the fact that after the coin passes the extremity of the noses 35 of either dog 33, the nose of the dog will act upon and impart a movement or a push to the coin, starting it down the inclined flange or wall 44. Obviously the coin will receive momentum enough to roll over the hurdle. However, a slug constructed of too light a 85 material, though it be of the proper diameter, will not receive momentum sufficient to override the hurdle. This is particularly due to the fact that the weight of the ball 41 will bear upon the edge of the slug, and hence act to retard it; therefore as the momentum is counteracted before the slug reaches the hurdle 47, the momentum will not be sufficient to carry the slug over the 90 hurdle.

A coin of a larger diameter, though it may pass the nose 35, will wedge between the ball 41 and the inclined bottoms or walls 44, hence not only blocking the coin passage or chute, but also preventing the dog 33 from being tilted when forcing another coin through the slots 3 and 4. The prevention of a slug of 100 too large a diameter passing through the coin passage or chute, is assured, due to the fact that when the slug wedges between the lower ends of the slots 3 and 4 and the nose 35 of the dog 33, the tail portions of the dogs will actuate, as to cause the notches 42 to straddle the balls 41, and hold them in the lower portions of the arcuate slots 40, thereby assuring the wedging of the slug between the member 41 and the bottom or wall 44 of the coin passage.

A headed pivot pin 48 projects from the rear wall of the inner casing, and pivotally mounted thereon is a slug clearing pawl 49, which is shown in Figures 2, 3 and 4, and particularly in the detail view of Figure 7. This pawl 49 has a downwardly projecting arm 50 provided with a lateral lug 51. The 125

edge 52 of the arm 50 contacts with the wall 53 of the depression 26 in the rear wall of the inner casing, thereby limiting the slug clearing pawl to its normal position. The 5 slug clearing pawl has an arm 54 provided with a headed pin 55, on which the trip detent 56 is mounted. The projecting arm 57 of the trip detent engages the annular shoulder 58 caused to be formed by the headed 10 pivot pin 48, holding the trip detent rigid relatively to the arm 54 of the pawl 49, that is to say when the bar 8 carried by the actuator is in its normal position. The detent 56 also has a projecting lug 59 and a hook 60. 15 A spring 61 has one end connected to the hook 60, while its other end is connected to a struck up lug 62 of the rear wall of the inner casing. This spring 61 holds the arm 57 normally in contact with the annular 20 shoulder 58, as long as the bar 8 is in its normal position. However, when the actuator is moved upwardly and the bar 8 likewise moved, the lug 25 of the bar 8 will contact with the lug 59 and trip detent, so that on 25 the downward movement of the bar 8 toward its normal position, the end edge of the lug 25 will cam against the surface 63 of the detent, and due to the arm 57 being in contact with the shoulder 58, the slug clearing pawl 30 will be tilted upon its pivot, causing the arm 50 to move under the permanent horseshoe magnet. The slug clearing pawl has an upwardly extending arm 64, which is curved and assumes a position in the coin passage 35 or chute. This arm 64 has a forward lug 65 operating in the arcuate slot 66. The extremity of the arm 64 has a rearwardly extending lug 67, which rides upon the inner surface of the rear wall of the inner 40 casing. It will be noted that the lug 67 will move in a path adjacent the arcuate edge 43 of the rear plate or wall 27 of the coin chute or passage, and each coin passing through the chute or passage necessarily 45 passes this lug 67 and the inclined wall 68 of the coin chute or passage.

A magnet holder 69 constructed of any suitable insulating material preferably "bakelite" is mounted within the inner casing, and is engaged under the flange 70, which is struck up from one of the side walls of the inner casing. A permanent horseshoe magnet 71 is housed in this bakelite holder 69, and it will be noted, as clearly 50 shown in Figure 8, that the rear of this holder 69, is cut away, so as to expose the rear faces of the arms or poles of the permanent magnet, this cut-away portion constituting and forming part of the lower end 55 of the coin passage or chute. This bakelite holder with its magnet may be held in the inner casing in any suitable manner (not shown). The lower extremities of the arms of the permanent magnet on their rear faces 60 have shoulders 72, which are adapted to en-

gage a magnetizable slug that may be passed into the upper part of the passage.

It is obvious that when a slug of proper weight and diameter and of suitable magnetizable material, is passed through the 70 coin passage or chute, it will be attracted and detained by the permanent horseshoe magnet, which will block another coin or slug in its passage through the machine. When a magnetizable slug is arrested by 75 the magnet, it will rest upon the shoulders 72, and though the machine may be jarred or shaken, it is practically impossible to cause the removal of the slug. When the slug is caught in this manner, and the operator who is fraudulently attempting to operate the machine, should push up on the actuator, the bar 8 will likewise move up, and the ears 12 will cover the coin receiving slots 80 3 and 4. However when pressure upon the actuator is relieved, and the bar 8 and the actuator are returned to their normal positions by the spring tensioned pawl 15, the lug 25 will engage with and cam upon the lug 59 of the detent, causing the arm 57 to 85 engage the shoulder 58. The detent and the slug clearing pawl will then move together, which will cause the arm 50 of the slug clearing pawl to move behind the permanent magnet. The lateral lug 51 of the arm 50 will immediately contact with the margin or the edge of the slug, and hence will prevent a sufficient movement of the pawl 49, to permit the lug 25 to pass the lug 59, thereby locking the fraud preventing 90 mechanism. In locking the mechanism in this manner the lug 67 will remain in the center of the coin passage or chute, while the ears 12 will remain in position covering the slots 3 and 4, thereby preventing another operator from attempting to actuate 95 the vending machine. The rear wall of the inner casing is provided with an elongated protuberance 73, which is formed by embossing the wall. This protuberance 73 is 100 positioned relatively to the magnet, and to the other parts of the mechanism, so as to cause an irregular movement of the coin, during its passage through the chute. It is obvious that in causing this irregular 105 passage of the coin, the coin will be swept near the rear face of the magnet. This will not affect the passage of a coin of proper diameter, weight and denomination (which is designed to be five cents), but should the slug or piece passing through the passage be 110 constructed of steel, iron or any other magnetizable material, it will assuredly be arrested by the magnet, due to the protuberance sweeping it close to the magnet. The closeness of the slug will insure the attraction of the slug to the magnet, thereby 115 causing it to be arrested, and consequently 120 block the operation of the mechanism.

The upper transverse portion 11 of the 125

bar 8 is provided with the depending arm 74, the lower edge 75 of which engages and rests upon the lug 68^a of the slug sweeping pawl 49, thereby not only assisting in limiting the bar 8 and the actuator in its returned normal position, but also assisting in returning the pawl 49 to its normal position.

The magnet holder 69 is provided with a protuberance 76, which engages in the notch 77 formed in the back wall of the inner casting 2, thereby preventing the holder as well as the magnet from moving vertically. Forward movement of the holder 69 is prevented, due to the fact that the flange or narrow portion 78 of the holder engages under the flange 70, which is struck up from one side of the inner casing 2.

It will be noted that the distance between the lower end of the coin slots 3 and the nose 35 of the adjacent dog 33 is normally less than the diameter of a coin of proper size, therefore upon the insertion of a coin of proper size the noses 35 of the coin dogs 33 will cam upon the coin, causing the dogs to oscillate. After a coin has passed the nose 35 of either coin dog, the action of the springs 38 returns the coin dogs 33 to their normal position, allowing the coin of proper size to pass through the chute.

Should a slug of a diameter larger than the proper diameter of coin, and of a greater thickness, or of irregular shape be forced into the coin slots 3 and 4 of either side of the casing, it will not, due to its oversize or irregularity, have a free passage through the chute and will either jam or lodge in the chute, and upon the subsequent attempt to insert a coin of proper diameter through the coin slots of the opposite side of the casing, the coin will not pass, due to the concerted action of the geared connections between the coin dogs. In other words the slug of oversize diameter will hold the coin dogs partly actuated, and upon the insertion of a subsequent coin of proper diameter, the coin dogs cannot make a full stroke, hence the coin of proper size cannot pass. In this way a subsequent operator is protected, and prevented from depositing a coin in a machine which is out of order.

It will also be noted that an attempt to force a coin into the coin slot on the blocked side of the contracting chute or coin passage would be of no avail, for during such an attempt, the action of the coin dogs 33 would force the lodged object toward the coin slot, which in itself would block or obstruct the insertion of the coin. Should such forced attempts be made on the opposite side, the lower part or lower end of the opposite passage would be blocked, due to the over-size irregular shaped slug being hung in the opposite side of the chute, and in this way, as above explained, it will be impossible to force a coin into the coin slot

due to the concerted action of the coin dogs 33. However, should the oversize or irregular-shaped slug not block the lower end of the passage but be disposed at a certain point in the chute, it is possible to insert a coin of proper diameter and this coin will have free passage through the chute. For instance, I show in Figure 2 in the upper right hand corner of the figure in dotted lines, two slugs of proper diameter. One of these slugs is disposed immediately opposite the ball 41, while the other slug is shown as adjacent the coin slot 3. Now if a slug should lodge immediately beneath the pivotal point for the bottom of 33, the dog can oscillate, so that while the right hand coin chute is blocked, yet a coin of the proper diameter, thickness and weight may pass down the opposite coin slot and between the other gravity actuated member 41 and the member 44. Thus one side of the coin chute or passage is blocked, but if this slug be disposed higher up as, for instance, as the entrance of the coin chute, as shown at the extreme right hand of Figure 2, then it will lift the portion 35 of the dog, depressing the inner end of the dog, and this will depress the inner end of the opposite dog and will limit the upward movement of the ball 41 on this last named side so that this chute will be prevented from receiving a coin due to the fact that the opposite chute is blocked.

The lug or ear 65 which is on the pawl 49 enters the arcuate slot 66 of the forward wall or plate 30 of the coin passage or chute, and is designed for directing the coin under the lug 67, which also forms a portion of the upper end of the arm 64 of the pawl 49. In other words the coin during its passage through the coin chute, may possibly contact or engage with the lug or ear 65 at a point, where said lug or ear bends or extends from the arm 64. At such time when a coin contacts with the lug or ear 65, it will be deflected toward the rear wall of the coin passage, thereby permitting the coin to pass under the lug or ear 67. The coin, upon being deflected toward the rear wall of the coin passage, is in an alignment with and enabling it to easily strike or contact with the hurdle 73, which will force the coin toward the magnet. If, instead of the coin, a steel slug of proper diameter and thickness be deflected toward the magnet, it will be attracted and detained thereby, which will prevent actuating the machine.

The detent 56 has a free movement on its headed pivot pin 55, that is for a limited distance. The spring 61 exerts a tension on the arm 54 of the pawl 49, since the detent is carried by the arm 54 of the pawl 49, and also exerts a clockwise tension on the detent, which, however, has no clockwise movement with relation to the pivot 14,

when the bar 8 is moving downward, as it is held from such movement by its lower arm 57 resting against the shoulder 58 of the pawl 49. The slug catching pawl 49 is 5 so designed that its lower end rests upon the rear wall of the depression 26, while its upper end extends a proper distance and terminates with a rightangle lug 67, which also rests upon the rear wall of the depression 10 26.

After a coin of proper diameter and thickness has passed through the contracted chute, and then passes under the upper arm of the 15 magnet, it will then pass through the lower part of the coin chute below the magnet, and then into proper position in the coin controlled mechanism or the article tray (not shown). The actuator may then be 20 pushed upwardly, accomplishing the delivery of the gum or other article to be vended. Upon the return of the actuator to its normal position, the lug 25 of the bar 8 will engage the detent 56, and cause the slug 25 catching pawl 49 to make an idle movement or stroke under the magnet, and also under the lower part of the forward wall or plate 30 of the coin chute or passage, unless there 30 is something in its path, in which event the machine is locked against the further depositing of a coin, due to the closing bar not being able to return to its normal position.

As previously stated if the slug catching pawl 49 does not, through some cause, return to its normal position, the coin slot closing bar cannot return to its normal position, due to the lug 25 being unable to pass the detent 56, or due to the end edge 75 of the projection 74 contacting with and resting upon the lug or ear 68^a of the arm 64 of the slug catching pawl; that is to say when the bar 8 has been moved to its fullest extent, and due to the coin slot closing ears 12 being unable to uncover the coin slots 3 and 4, since the bar is unable to return to its normal position, the machine is locked, and the depositing of another coin prevented.

Should a slug of the proper size for which 50 the magnet has attraction be inserted in the machine, it will make its way to the coin passage or chute until it reaches the magnet where it will be arrested from further movement. It is not possible to shake the slug 55 from engagement with the magnet, due to the shoulders 72 on the arms of the magnet. Also due to the protuberance or boss 73 formed in the rear wall of the depression 26, it is impossible for another slug to pass by the 60 slug already arrested by the magnet, for the passage is not large enough to permit the second slug or coin to pass between the boss or protuberance, and the first slug or coin. The slug which is held by the magnet is 65 directly in the path of the stroke of the slug

catching pawl 49, which will not be able to make its stroke and therefore will hold the slot closing bar in a raised position.

The invention having been set forth, what is claimed as being useful is:

1. In a fraud preventing mechanism for vending machines, a coin chute or passage having in its upper wall a pivoted dog, a gravity actuated member carried by the dog and normally projecting into the passage 75 and acting to impede the movement of a coin down said passage and having limited outward movement in the dog.

2. In a fraud preventing mechanism for vending machines, a coin chute or passage 80 having a hurdle partly in the path of a slug of underweight, said chute or passage having a gravity actuated contracting wall section to retard the momentum of the slug, thereby preventing it from rolling over the 85 hurdle.

3. In a fraud preventing mechanism for vending machines, a coin passage or chute having coin slots, coin dogs cooperating with the ends of said slots for gauging the 90 coin to pass therethrough, said coin chute or passage having gravity movable wall sections under which the coin passes, said coin dogs having means cooperating with the gravity movable wall section to prevent 95 movement of the same, and thereby retarding an over-size diameter of slug.

4. In a fraud preventing mechanism for vending machines, a coin chute or passage having branch parts, through either one of which a coin is adapted to pass, said branch parts of the coin passage having interconnected coin dogs, to cooperate with the ends of the branch parts of the passage, so that a slug having an oversize diameter may 100 cooperatively wedge between the lower wall of one of the branch parts of the passage and the end of its respective dog, for locking the dogs in their actuated positions, thereby closing both branch parts of the coin passage. 105

5. In a fraud preventing mechanism for vending machines, a coin chute having coin receiving branch parts having coin slots, coin dogs mounted in the upper parts of the 110 branch parts of the coin chute and constituting walls, tensioning means for the dogs, intergeared connections between the dogs so that the operation of one actuates the other, coin jumping hurdles in the branch parts to retard the momentum of the coin.

6. In a fraud preventing mechanism for vending machines, a coin chute having coin receiving branch parts having coin slots, coin dogs mounted in the upper parts of the 115 branch parts of the coin chute and constituting walls, tensioning means for the dogs, intergeared connections between the dogs so that the operation of one actuates the other, coin jumping hurdles in the branch parts to 120 retard the momentum of the coin, and 125

- gravity actuated wall sections operatively mounted in the branch parts of the coin chute to cooperate with a slug of too light a material, for retarding the momentum of 5 of the slug, and thereby preventing the same from properly passing the hurdle.
7. In a fraud preventing mechanism for vending machines, a coin chute having coin receiving branch parts having coin slots, 10 coin dogs mounted in the upper parts of the branch parts of the coin chute and constituting walls, tensioning means for the dogs, intergeared connections between the dogs so that the operation of one actuates the other, 15 coin jumping hurdles in the branch parts to retard the momentum of the coin, and gravity actuated wall sections operatively mounted in the branch parts of the coin chute to cooperate with a slug of too light 20 a material, for retarding the momentum of the slug, and thereby preventing the same from properly passing the hurdle, and means carried by the coin dogs cooperating with the gravity wall sections, to hold the wall 25 sections against movement, in case a slug is wedged between the dogs and the lower ends of the coin slots.
8. In a coin actuated machine, a coin passage, a vertically movable ball operating in 30 guides in said passage and normally held by its own weight in the path of movement of the coin but adapted to be lifted by a coin, means actuated by the insertion of a blank of larger diameter than the predetermined coin to prevent the outward movement 35 of said ball.
9. In a machine as set forth a coin passage having an inclined surface to permit 40 a coin to roll, and a hurdle at the lower end of said passage, over which the coin passes, and a gravity actuated wall section to retard the momentum of a slug of light material, hence preventing the slug from passing over 45 the hurdle.
10. In a machine as set forth a coin passage having an inclined surface to permit a coin to roll, and a hurdle at the lower end of said passage, over which the coin passes, and a gravity actuated wall section to 50 retard the momentum of a slug of light material, hence preventing the slug from passing over the hurdle, and means to lock the gravity movable wall section in place.
11. In a mechanism as set forth, a coin chute, a hurdle in the path of a coin, and a gravity movable spherical means cooperating 55 with the hurdle to retard the movement of a slug of underweight material, thereby preventing its passage through the chute.
12. In a fraud preventing mechanism for vending machines, a coin chute provided with coin receiving slots, said chute having opposed front and back walls provided with 60 arcuate slots, and gravity members guided in said arcuate slots and adapted to be 65 lifted by the weight of the coin to permit the coin to pass through the chute.
13. In a fraud preventing mechanism for vending machines, a coin passage or chute having an inclined bottom, the front and back walls of the chute having guides, a gravity wall section mounted in said guides and under which the coin is adapted to pass, to permit the coin to pass onward through the chute, and spring tension means 70 actuated by a coin as it enters the chute to hold the gravity wall section in position until after the coin reaches an obstructing position ready to pass under the wall section. 75
14. In a fraud preventing mechanism for vending machines, a coin passage or chute having an inclined bottom, the front and back walls of the chute having guides, a gravity wall section mounted in said guides and under which the coin is adapted to pass, to permit the coin to pass through the chute, and a hurdle below the gravity wall section. 80
15. In a fraud preventing mechanism for vending machines, a coin passage or chute having an inclined bottom, the front and back walls of the chute having guides, a gravity wall section mounted in said guides and under which the coin is adapted to pass, to permit the coin to pass through the chute, and a hurdle below the gravity wall section. 85
16. In a coin actuated machine, an inclined coin passage, means for retarding a coin in its passage or for blocking an over-sized blank comprising a gravity actuated 90 movable member disposed in the top wall of the coin passage and normally extending into the path of a coin but lifted by a coin of proper size, and means actuated by the insertion of a coin in the entrance to the coin passage limiting the upward movement 95 of said gravity actuated member. 100
17. In a coin actuated mechanism, a coin chute provided with a gravity actuated wall in the top wall of the chute to be engaged and lifted by a coin of predetermined diameter, means actuated by the insertion of a slug larger in diameter than the predetermined coin acting to limit the upward movement of the gravity wall and thereby prevent the slug from passing down the chute. 110
18. In a coin actuated mechanism, a coin passage having a dog pivoted intermediate its ends and forming a wall section of the coin passage, a gravity actuated member normally disposed in the path of movement of the coin down said passageway, the dog under normal circumstances permitting the lifting of the member by pressure of a coin 115 120 125 130

but when engaged by a slug or coin of larger than the predetermined diameter preventing upward movement of the member to thereby prevent the descent of the coin or 5 slug through said passage.

19. In a coin operated mechanism, a coin chute, a dog pivoted adjacent the entrance to the coin chute and having that end adjacent the entrance to the coin chute formed 10 with a slightly concave under edge surface

adapted to engage the coin, a spring holding the dog in a normal position, the curved portion of the dog being lifted by the insertion of a coin against the action of said spring and the dog then acting to kick the 15 coin along the coin chute by the resilience of said spring.

In testimony whereof I hereunto affix my signature.

JAMES HERVEY MANN, JR.
